UNITED STATES PATENT OFFICE

138,777

DESIGN FOR A TOY

Richard C. Lewis, Winnetka, Ill.

Application July 3, 1944, Serial No. 114,286

Term of patent 14 years

(Cl. D34—15)

To all whom it may concern:

Be it known that I, Richard C. Lewis, a citizen of the United States of America, residing at 1386 Asbury Avenue, Winnetka, Illinois, have invented a new, original, and ornamental Design for a Toy, of which the following is a specification, reference being had to the accompanying drawing, forming a part thereof.

Referring to the drawing, Fig. 1 is a perspective view of a toy embodying my new design; Fig. 2 is a front elevational view and Fig. 3 is a top plan view of the same.

I claim:

The ornamental design for a toy, substantially as shown.

RICHARD C. LEWIS.
